UNITED STATES PATENT OFFICE.

FRANCIS M. BROWN, OF WILSON, OKLAHOMA.

BRACE.

Application filed May 9, 1921. Serial No. 468,019.

To all whom it may concern:

Be it known that I, FRANCIS M. BROWN, a citizen of the United States, and a resident of the city of Wilson, in the county of 5 Carter and State of Oklahoma, have invented a new and useful Improvement in Braces, of which the following is a full, clear, and exact description.

My invention relates to improvements in 10 braces, and it consists in the combinations, constructions and arrangements herein described and claimed.

An object of my invention is to provide a brace having a chuck of greater capacity 15 in a given size than is usual.

A further object of my invention is to provide in a device of the character described a chuck having adjustable gripping members adapted to effectively hold tools of 20 various sizes.

A further object of my invention is to provide in a device of the character described a chuck having gripping members easy of adjustment.

25 A further object of my invention is to provide a device of the character described that is relatively simple in construction, and operation, not likely to get out of order easily, and thoroughly practical commercially.

Other objects and advantages will appear in the following specification, and the novel features of the invention will be particularly pointed out in the appended claim.

35 My invention is illustrated in the accompanying drawings, forming part of this application, in which—

Figure 1 is a side elevation of the device, portions thereof being broken away and 40 other portions being shown in section,

Figure 2 is a section along the line 2—2 of Fig. 1,

Figure 3 is a section along the line 3—3 of Fig. 2,

45 Figure 4 is a bottom plan view of a portion of the device, and

Figure 5 is an enlarged perspective of an element embodied in the device.

In carrying out my invention, I provide 50 a chuck having a stock or body portion 1 and an integral laterally extending shank or handle portion 2. The shank or handle portion 2 is bent upwardly adjacent to its end and formed with a threaded axial bore or 55 socket 3 adapted to receive the threaded end of a cooperating handle portion 4. A pin 5

is provided to prevent disengagement of the threaded extremity of the handle portion 4 and the socket 3.

The stock or body portion 1 is substantially cylindrical in form, the outer wall thereof being reduced and threaded at 6 for engagement with an interiorly threaded thimble 7. The stock or body portion 1 is formed to provide a substantially rectangular axial chamber or recess 8 of relatively great length. The recess 8 extends from the lower end of the stock upwardly and the end walls 9 and 10 converge from points intermediate their height to a central opening 11 through the upper wall of the stock, which is otherwise imperforate. The side walls of the recess 8 are straight and parallel with one another adjacent to their extremities and are formed with similar recesses 12 and 13, respectively, intermediate, as clearly shown in the drawings. The recesses 12 and 13 are defined by inclined walls converging from the lower end of the stock 1 to the opening 11 and the walls of each recess join one another at a right angle.

80 The chamber or recess 8 provides a guideway for a pair of precisely identical gripping members or dogs 14—14 each of which has its rear face beveled adjacent to its ends, as at 15 and 16, and is formed with oppositely extending integral lateral lugs 17 and 18, respectively, intermediate its length. Each gripping member or dog has its front face provided with transversely extending 85 teeth 19 for its entire length, these teeth being intersected intermediate by a longitudinally extending right angular groove or recess 20 in the face of the dog. The lug 17 is provided with an opening 21 therethrough and the lug 18 is provided with an elongated opening 23 therethrough. Pins 22 are disposed in the aligned openings 21 and 23. It will be noted that this construction permits the dogs 14 to move angularly with respect 90 to each other.

95 From the foregoing description of the various parts of the device, the operation thereof may be readily understood. The parts described may be made of any suitable 105 materials, such as are commonly used in the manufacture of like devices. When the gripping members or dogs 14—14 are arranged to face each other in the guideway, it is obvious that the elongated opening 23 of one 110 dog will be opposite the opening 21 of the other dog. The rods 22 and 23 are projected

through alined openings and the ends of these rods are then upset after springs 25-25 have been placed thereon between opposite lugs to urge the dogs apart. As the 5 gripping members or dogs 14-14 are moved upwardly in the recess 8, the upper beveled portion of the outer or rear face of each dog will slidably contact the converging portion of the adjacent end wall of the recess 8. The movement of the dogs together is occasioned by operation of the thimble 7 which has a tapering end portion 26 adapted to slidably contact the lower beveled portion 10 of the outer face of each dog as the thimble is turned on the stock or body portion 1. An inwardly extending annular shoulder 27 at 15 the junction of the tapering portion of the thimble with the cylindrical main portion thereof provides a means for limiting the movement of the lower portions of the dogs apart when the thimble engages the stock 20 or body portion 1. Since each of the rods 22 and 22 may oscillate vertically at one end on account of fitting the elongated opening 25 23 loosely, it is obvious that the dogs 14-14 will remain parallel with one another when urged apart by the springs 25-25 and permitted to move downwardly and outwardly, as when the thimble is turned in one direction, but that the corresponding ends of the 30 dogs may converge and diverge to grip the tapering shank or head of a tool bit 28 when the dogs are moved inwardly and upwardly against the tension of the springs 25-25 35 when the thimble is moved in the opposite

direction on the body portion 1. It is obvious that tool bits ranging in size from a very small size to a relatively large size may be effectively gripped between the serrated faces or jaws of the dogs 14-14 and that my device has a greater capacity in a given size than is ordinary. Since a larger portion of the tool engaged is gripped in my device than is ordinarily the case, it is apparent that the tool bits will be more securely held 40 in operative position than has heretofore been possible in any device of like character of which I am aware. My improved device can be operated quickly and easily to engage and disengage tools, as desired. 50

I claim:

In a device of the type described, a body portion having a tapering square centrally disposed opening therein, said body having diametrically disposed converging grooves 55 communicating with the opening, a pair of dogs, each dog having two laterally projecting lugs with openings therein, one of the openings of each dog being elongated, pins disposed in the alined openings of each dog, coil springs carried by said pins and being disposed between said dogs, and a cylindrical casing carried by said body portion and housing said dogs, said casing being adapted, when rotated in one direction, to move said 60 dogs toward each other the elongated openings permitting said dogs to move angularly with respect to each other. 65

FRANCIS M. BROWN.
